US0D1108312S

(12) United States Design Patent (10) Patent No.: US D1,108,312 S
(45) Date of Patent: * Jan. 6, 2026

(54) MOTORCYCLE FRAME

- (71) Applicant: Indian Motorcycle International, LLC, Medina, MN (US)
- (72) Inventors: Richard J. Christoph, Medina, MN (US); Ola I. Stenegard, Stanga (SE); Jeffrey D. Oltmans, North Branch, MN (US)
- (73) Assignee: INDIAN MOTORCYCLE INTERNATIONAL, LLC, Medina, MN (US)
- () Term: 15 Years
- (21) Appl. No.: 30/004,987
- (22) Filed: May 22, 2025

Related U.S. Application Data

- (62) Division of application No. 29/892,023, filed on May 12, 2023, now Pat. No. Des. 1,076,762, which is a division of application No. 29/764,281, filed on Dec. 29, 2020, now Pat. No. Des. 990,374.

(57) CLAIM

The ornamental design for a motorcycle frame as shown and described.

DESCRIPTION

FIG. 1 is a front-right side perspective view of a motorcycle frame embodying our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines in the drawings illustrate portions of the motorcycle frame that form no part of the claimed design.
